UNITED STATES PATENT OFFICE.

LEO JOHN BAYER, OF ST. LOUIS, MISSOURI.

METHOD OF MANUFACTURING METAL TUBING.

Application filed July 15, 1927. Serial No. 206,004.

The present invention has relation to improvements in the methods of manufacturing metal tubing, and it consists in the novel features more fully set forth in the specification and pointed out in the claims.

My improved tubing is particularly adapted to withstand the corrosive effects of furnace gases and is for use, therefore, primarily in soot blowers or other apparatus in connection with boilers which are exposed to the furnace gases.

The principal object of the invention is to provide a tube having the property above pointed out, at a low cost, and by a method that is simple. I have found that this can best be done by combining an ordinary rolled steel tube with a thin sheath of chromium steel to form a composite tube. Thus the advantage of the corrosion resisting properties of the chromium steel are obtained only on the outer surface of the composite tube where needed. The cost of the composite tube is much less than an all chromium alloy tube, and the difficulties of fabricating an all chromium alloy tube are avoided.

Further advantages will be better apparent from a detailed description of the invention in connection with accompanying drawings, in which:

Figure 1 is a side elevation of a piece of soot blower tube, or element, made according to the teachings of this invention; Fig. 2 is an enlarged longitudinal section taken on a medial plane of a piece of the blower tube; Figs. 3 and 4 are vertical cross-sections taken on the line 3-3 and 4-4 respectively of Fig. 1; Fig. 5 is a development of one of the sections of sheathing enclosing the ordinary tube; and Fig. 6 is an edge view of said section before being rolled into a tube.

Referring to the drawings, T represents a piece of soot blower element comprising an ordinary steel tube 1 with a plug 2 welded into one end, and a chromium alloy steel sheathing S enveloping said tube 1. Steam nozzles 3 pass through the sheathing and are welded or otherwise secured into the tube 1.

The sheathing S comprises a plurality of telescoping cylinders 4, 4 etc., each of which is rolled from a blank *a*, the side edges 5, 5 of which are bent over and the corners 6, 6 at one end cut out, as shown in Fig. 6.

When the blank *a* is rolled into a cylinder the edges 5, 5 are brought together to form a lock-seam 7 and the cut out corners 6, 6 form a notch 8. After the blanks have been rolled into cylinders the end 9 having the notch 8 is spread or swaged sufficiently so that it will receive the opposite end of a similar cylinder. Obviously the presence of the notch 8 instead of the seam 7 at one end of the cylinder 4 enables this end to be easily spread and at the same time provides a recess to receive the end of the next adjacent cylinder or section.

The cylinders 4 are of a diameter compared to the tube 1, that they will just slide over said tube. Preferably there should be no appreciable space between the tube and sheathing. The chromium content of the steel from which the blanks *a* are stamped is not critical, but may be anywhere between 15% and 35%. Then, too, some other steel alloy may be used with equal advantage if it possesses the property of resisting corrosion and oxidation when exposed to the action of hot furnace gases.

If the entire blower element were made of chromium alloy steel it would necessarily have to be of a thickness that would render it difficult to roll. On the other hand, merely providing the blower tube with a thin sheathing enables one to roll even a high chromium content alloy with comparative ease. In this manner I provide a blower element having lasting qualities equal to those of an element made entirely of chromium alloy at a greatly reduced cost.

Having described my invention, I claim:

1. The method of fabricating elements for soot blowers, which consists in rolling thin blanks of non-corrosive and non-oxidizing steel alloy into cylinders, spreading one end of each cylinder sufficiently to receive the unspread end of another cylinder, sliding a plurality of said cylinders over an ordinary steel tube and causing adjacent cylinders to be joined in telescopic relation.

2. The method of fabricating elements for soot blowers, which consists in rolling thin blanks of non-corrosive and non-oxidizing steel alloy into cylinders, forming the abutting ends of each cylinder into a seam, cutting out the seam at one end of each cylinder to form a notch, spreading the notched end of each cylinder sufficiently to receive the unspread end of another cylinder, slid-

ing a plurality of said cylinders over an ordinary steel tube and causing adjacent cylinders to be joined in telescopic relation.

3. The method of fabricating elements for soot blowers which consists in rolling thin blanks of non-corrosive and non-oxidizing steel alloy into cylinders, sliding a plurality of said cylinders over an ordinary steel tub

and causing the adjacent cylinders to be intimately connected, perforating the composite tube and cylinder, and fixing a nozzle in the perforation of the tube. ¹⁰

In testimony whereof I hereunto affix my signature.

LEO JOHN BAYER.
